ABSTRACT: Disclosed is a J-K master-slave flip-flop system having a simplified gating system and in which no clock pulse connections are required for the transfer transistors. Clock pulses are fed to input gates. Additional clocks may be added by tying the input gates to clock lines. The clock pulse are ANDed together at the input gate so that the J-K master-slave flip-flop system is suitable for use in large arrays.

Fig. 2

J-K MASTER-SLAVE FLIP-FLOP

The present invention relates to electrical flip-flop circuits and more particularly to J-K master-slave flip-flop circuits.

An object of the invention is to provide a J-K master-slave flip-flop with a minimum load upon the clock.

Another object of the invention is to provide a J-K master-slave flip-flop which is entirely free of internal race conditions.

Other objects, features and advantages of the invention will be best understood by reference to the following detailed description when read in conjunction with the appended claims and attached drawings in which like reference symbols indicate like parts and in which:

FIG. 1 illustrates a block diagram of a J-K master-slave flip-flop according to the present invention;

FIG. 2 illustrates embodiment of a J-K master-slave flip-flop according to the invention;

FIG. 3 illustrates a TTL NAND gate used in the embodiment of FIG. 2;

FIG. 4 illustrates a timing diagram of the operation of the embodiment of FIG. 2; and

FIG. 5 illustrates a timing diagram of the operation of the embodiment of FIG. 2; and

FIG. 5 illustrates the input-output transfer characteristics of the TTL NAND input-gates of the embodiment of FIG. 2.

Referring to FIG. 1, a block diagram of a J-K master-slave flip-flop according to the present invention is illustrated and indicated by reference No. 9. Input information is received through the J_i - K_i inputs to the input gates 11 and 12. A clock pulse from the clock 13 and an output feedback from each of the output circuits 16 and 17 are also received at the two input gates 11 and 12. Information is entered from the J_i - K_i inputs to the master flip-flop 10 when the clock pulse goes high, that is when the positive edge of the clock pulse occurs. The information stored in the master flip-flop 10 is then transferred through the transfer gates 14 and 14A to the slave flip-flop 15 when the clock pulse goes low, that is, when the negative edge of the clock pulse occurs. The state of the slave flip-flop appears at the outputs Q and $\bar{Q}$ as binary high-low voltage level outputs from the output circuits 16 and 17.

The clear and preset controls (shown in FIG. 2) allow the J-K master slave flip-flops 10 and 15 to be set to either state, $Q=1$ and $\bar{Q}=0$, or $Q=0$ and $\bar{Q}=1$. The input-output logic table for the J-K master slave flip-flop 9 is shown in Table I below:

TABLE I

J	K	Initial output		Final output ¹	
		Q	$\bar{Q}$	Q	$\bar{Q}$
1	1	1	0	0	1
1	1	0	1	1	0
1	0	1	0	1	0
1	0	0	1	1	0
0	1	1	0	0	1
0	1	0	1	0	1
0	0	1	0	1	0
0	0	0	1	0	1

¹ Compliments initial output.

It is to be noted that in the logic shown in Table I, the logic state 1 is to be represented by a high voltage and the logic state 0 is to be represented by a low voltage.

Referring to FIG. 2, a J-K master slave flip-flop designed according to the present invention is illustrated. The master slave flip-flop is comprised of six TTL NAND gates, G_1 - G_6 , two transfer transistors T_1 and T_2 , six output transistors T_3 - T_8 , sixteen resistors R_1 - R_{16} , one reference diode D, and two biasing voltages V_{cc_1} and V_{cc_2} . The gates G_1 and G_2 and resistors R_1 - R_4 comprise the two input gates for the master slave flip-flop. The gates G_3 and G_4 and resistors R_5 and R_6 comprise the master flip-flop which is set in accordance with the J-K inputs to gates G_1 and G_2 when the positive edge of the clock pulse occurs. Gates G_1 - G_4 are connected to ground through the reference diode D. Transistors T_1 and T_2 comprise the transfer gates 14 and 14A of FIG. 1 respectively. They are

the means of information transfer between the master flip-flop 10 and the slave flip-flop 15. T_1 and T_2 isolate the master flip-flop 10 from the slave flip-flop 15 while the master flip-flop 10 is being set at the positive edge of a clock pulse and transfers the information from the master flip-flop 10 to the slave flip-flop 15 at the negative edge of the clock pulse.

Gates G_5 and G_6 and resistors R_7 - R_{10} comprise the slave flip-flop 15 which is set in accordance with the information received from the master flip-flop through transistors T_1 and T_2 at the negative edge of the clock pulse. Transistors T_3 - T_8 and resistors R_{11} - R_{16} comprise output circuitry 16 and 17 which provides the J-K master slave flip-flop with low output impedance, low noise pickup and good capacitive drive characteristics. The binary output of the master slave flip-flop, Q and $\bar{Q}$, is taken from the output circuitry.

Referring to FIG. 3, each of the six TTL NAND gates shown in FIG. 2 comprises two NPN transistors T_i and T_o and biasing resistors R_a and R_b . T_i is a multiple emitter transistor and its several emitters comprise the inputs to the NAND gate. The base of T_i is connected to the biasing voltage V_{cc} through R_a and the collector is connected to the base of the output transistor T_o . The collector of T_o is connected to the biasing voltage V_{cc} through R_b and its emitter is connected to ground through the diode D (gates G_1 - G_4) or through a passive resistance (gates G_5 and G_6).

The voltage states of the T_i input emitters determine whether T_o will be in the On or Off state as the current of transistors T_i flows either through the base-collector P-N junction thereof or through one of the base-emitter P-N junctions. If the inputs to all emitters of T_i are in the high state, the base-emitter P-N junctions will all be reverse biased and current will flow through the base-collector junction to the base of T_o , turning T_o On. If one or more of the emitter inputs of T_i are low, the respective base-emitter P-N junctions of such emitters will be forward biased and the current of transistor T_i will be diverted from the collector to such emitters. In this state no drive current reaches the base of T_o and T_o is turned Off.

The input threshold voltage for a high input is determined by the voltage across the external circuitry Load plus the base-emitter voltage V_{be} of output transistor T_o . Any input emitter voltage to T_i below this level will forward bias the base-emitter junction of the emitter to which it is applied. When all T_i emitters are high, the drive current to transistor T_o is sufficient to saturate it, causing its collector voltage to go low. When no drive current reaches T_o , T_o is Off and the collector is at the high voltage impressed upon it by V_{cc} . The output of the NAND gate is the voltage of the T_o collector. It is to be noted that for the TTL NAND gate illustrated, the logical state 1 is represented by a high voltage and the logical state 0 is represented by a low voltage.

Transistors T_1 through T_8 (in FIG. 2) are NPN transistors with suitable saturation characteristics for digital circuitry use. Diode D is a P-N junction semiconductor diode.

The functional relationships between the components of the master-slave flip-flop may be best understood by reference to the operation of the flip-flop in response to a sample set of inputs while in a given initial output state. For purposes of this description, the assumed initial output state is Q in the logical 1 state and $\bar{Q}$ in the logical 0 state. The sample inputs are J_1 through J_3 in the logical 1 state, K_1 through K_3 in the logical 1 state, clear in the logical 1 state and preset in the logical 1 state. As seen from Table I above, after the clock pulse occurs, the output state will be Q in the 0 state and $\bar{Q}$ in the 1 state, the complement of the initial output state. As will become evident subsequently, for Q to be initially in the logical 1 state, that is at a high voltage, transistor T_1 must be On, transistor T_2 must be Off, gate G_3 must have a logical 1 output and gate G_4 must have a logical 0 output.

The timing diagram for the operation of the master-slave flip-flop under the conditions stated above is illustrated in FIG. 4 and will be referred to during the description of the flip-flop operation.

At time t_1 of FIG. 4, the J and K inputs and the positive edge of the clock pulse are all present at the input gates of the master-slave flip-flop. Referring to FIG. 2, gate G_1 has a low voltage logical 0 input from $\bar{Q}$, regardless of the clock and J inputs, forcing its output to the logical 1 state. It is thus disabled by $\bar{Q}$ and its logical output at the collector of transistor T_{o1} does not change. Gate G_2 , however, has all inputs in the logical 1 or high state. The base-collector junction of transistor T_{o2} is thus forward biased and base current is fed to transistor T_{o2} . Transistor T_{o2} begins to turn On in response to the base current it is now receiving. As transistor T_{o2} turns On, the output voltage at its collector begins to drop. When the voltage becomes sufficiently low, the emitter of transistor T_{o4} , which is connected to the collector of transistor T_{o2} , will begin to draw the transistor current of T_{o4} and transistor T_{o4} will be turned Off. As T_{o4} turns Off, its collector voltage rises. This voltage is connected to one of the emitter inputs of transistor T_{o3} . The other two emitter inputs of T_{o3} are connected to the collector of transistor T_{o1} and preset. Since these two inputs are in the logical 1 or high state, as T_{o4} turns Off, all inputs to T_{o3} reach the high state and T_{o3} is turned On. Gate G_3 now has a logical 0 or low output and gate G_4 has a logical 1 or high output. The master flip-flop has been set in accordance with the J-K inputs.

Transistors T_1 and T_2 effectively isolate the master flip-flop from the slave flip-flop during this setting of the master flip-flop. As noted above, T_1 was On prior to the occurrence of the positive edge of the clock pulse. As T_{o4} turns Off, however, the emitter of T_1 which is connected to the collector of T_{o4} goes high and the base emitter junction of T_1 is reverse biased and T_1 turns Off, causing its collector to go high. This has no effect on the slave flip-flop since gate G_{16} receives both the $\bar{Q}$ voltage and the T_1 collector voltage at its input emitters. Since $\bar{Q}$ remains low, the change in state of T_1 does not affect the gate G_6 .

Before the clock pulse, transistor T_2 was Off and effectively open circuited at its emitter by transistor T_{o3} which was then Off. Although T_{o3} turned On when the positive edge of the clock pulse occurs, T_2 remains Off. For T_2 to turn On, its base voltage would have to reach the voltage V_{be2} plus $V_{saturation\ 2}$ above the voltage of the reference diode D, where V_{be2} = the base-emitter forward diode voltage of T_2 , and where $V_{saturation\ 2}$ = the base voltage required for T_2 to operate in the saturated region. However, the voltage to the base of T_2 is the output voltage of the collector of T_{o2} . This voltage has dropped low enough to turn transistor T_{o4} On. Therefore, it must have gone below the voltage $V_{be4} - V_{offset\ 4}$ above the reference diode D, where V_{be4} = the base-emitter junction voltage of transistor T_{o4} , and where $V_{offset\ 4}$ = the difference between the base-emitter forward diode voltage and the base-collector forward diode voltage of T_{o4} above the reference diode D. So long as $V_{be2} + V_{saturation\ 2}$ is equal to or greater than $V_{be4} - V_{offset\ 4}$, the base voltage into transistor T_2 will have fallen below that required to turn On T_2 before T_{o3} is turned On. The low emitter voltage T_2 receives as T_{o3} turns On has no effect upon it and T_2 remains Off, preventing the setting of the master flip-flop from affecting the slave flip-flop. The difference in the two voltages $V_{be2} + V_{saturation\ 2}$ and $V_{be4} - V_{offset\ 4}$ insures the isolation of the master and slave flip-flops. The J-K master slave flip-flop is free of any "internal race" conditions as the transfer transistors eliminate the possibility of signals being transferred between the master and slave flip-flops at improper times. Even if the two voltages are the same, propagation delay through gates G_4 and G_3 required before the emitter of transistor T_2 goes low will prevent internal race. The same relationship that exists between transistors T_2 , T_{o2} and T_{o4} also exist between transistors T_1 , T_{o1} and T_{o3} to prevent internal race when the J-K inputs are such as to set the master flip-flop in the opposite sense to that described, causing the emitter of T_1 to go low. The collector of T_{o1} will be below $V_{be1} + V_{saturation\ 1}$ (V_{be1} = base-emitter forward diode voltage of T_1 and $V_{saturation\ 1}$ = the base voltage required for T_1 to operate in the saturated region) and T_1 will not be able to turn On.

The master flip-flop now contains the new information entered while the slave flip-flop contains the information entered previously. The transistors T_1 and T_2 isolate the two flip-flops.

At any time after the master flip-flop is set, the negative edge of a clock pulse may occur. In circuits built and tested, the time required for setting the master flip-flop has been as small as 7 nanoseconds. When the negative edge of the clock pulse occurs, gate G_1 remains unaffected due to the inhibiting effect of $\bar{Q}$ being low. However, with the clock now going low, the respective input emitter of T_{o2} to the base of transistor T_{o2} ceases, turning Off T_{o2} . As T_{o2} turns Off, the output voltage at its collector rises. As the collector voltage rises, it reaches $V_{be2} - V_{saturation\ 2}$, the base voltage required for T_2 to turn On and T_2 turns On. The input emitter to transistor T_{o3} connected to the collector of transistor T_2 is now connected to ground through T_2 , T_{o3} and the reference diode D. The input threshold for a high input to gate G_3 is set by the output transistor T_5 and resistors R_8 and R_{13} to be above the voltage across T_2 , T_{o3} and reference diode D. The voltage to the emitter of T_{o3} is thus sufficiently low to forward bias the respective base-emitter junction and the driving current from T_{o3} to T_{o5} ceases and transistor T_{o5} turns Off. This turns Off transistor T_5 and turns On T_3 and T_4 . The output biasing voltage V_{cc2} now drives transistors T_3 and T_4 with the result that $\bar{Q}$ is high. At the same time, T_{o4} is now Off and T_1 is essentially open circuited. The Q, T_1 and preset inputs to gate G_6 are now all high, with the result that T_{o6} is turned On and the collector voltage of T_{o6} goes low. Transistor T_6 is thus turned On and turns Off transistors T_6 and T_7 , with the result that Q goes low. The transfer of information from the master flip-flop to the slave flip-flop and output circuits has been accomplished and the outputs now are Q low or 0 and $\bar{Q}$ high or 1, as required by the logic of the J-K master slave flip-flop as given in Table I.

It can now be seen that when Q was in the initial high state, gate G_6 must have been receiving a low input from T_1 , and gate G_5 must have been receiving a high input from T_2 , that is, T_1 was On and T_2 was Off. For T_1 to be On, the output of gate G_4 had to be low, and for T_2 to be Off, the output of gate G_3 had to be high. This is the justification for the assumption of T_1 On, T_2 Off, and G_3 high, G_4 low, as the initial state of the flip-flop in the above description.

The operation of the J-K master slave flip-flop in response to the other possible combinations of input signals and to the clear and preset signals is similar to that described above. It is to be noted that if Q is to be initially low, gate G_2 is disabled and gate G_1 is enabled, whereas if $\bar{Q}$ is initially low, gate G_1 is disabled and gate G_2 is enabled. No change of output state will occur unless an enabled input gate receives all logical 1 inputs. Special reference is made to the clear and preset signals. The preset signal is received at gates G_2 , G_3 and G_6 and results in setting the master and slave flip-flops simultaneously so that Q is set to the logical 1 state and $\bar{Q}$ is set to the logical 0 state. The clear signal is received at gates G_1 , G_4 and G_5 , and results in the simultaneous setting of the master and slave flip-flops so that Q is set to the logical 0 state and $\bar{Q}$ is set to the logical 1 state. The present and clear signals are normally in the high or logical 1 state, so as not to affect the action of the gates. To cause preset or clear to occur, the respective signal is made to go low, causing a base-emitter forward biasing to occur at each of the multiple emitter transistors to which it is applied and forcing a high output for that gate.

Interconnecting the transfer transistors T_1 and T_2 with the input gates, G_1 and G_2 , the master flip-flop gates G_3 and G_4 and the slave flip-flop gates G_5 and G_6 in the configuration illustrated in FIG. 2 provides many advantages for the J-K master slave flip-flop.

The J-K master-slave flip-flop requires no clock pulse connections to the transfer transistors. The clock pulse line is connected only to the input gates G_1 and G_2 . This makes for a minimum power load upon the clock, a definite advantage in large arrays of flip-flops. With the clock being fed only to the input gates, more clocks can be added by simply tying the input emitter leads of the input gates to the clock lines. The

clock pulses will then be ANDed at the input gates. This is especially desirable where the J-K master-slave flip-flop is embodied in an integrated circuit and additional connections to the transfer gates cannot be made after fabrication.

The transfer transistors T_1 and T_2 connected in the configuration shown also provide the isolation between the master flip-flop 10 and the slave flip-flop 15 during the time that the master flip-flop 10 is being set and until the negative edge of the clock pulse occurs. The configuration uses the inherent junction voltages of the transistors in the gates G_1 — G_4 and the junction voltages and saturation voltages of the transfer transistors T_1 and T_2 to obtain total elimination of internal race conditions with a minimum of circuit components.

Because of this complete elimination of internal race conditions and the ANDing of the input signals at the input gates G_1 and G_2 , the J-K master-slave flip-flop according to the present invention is especially suitable for use in large arrays where several clock lines may be required to supply clock pulses to many J-K master slave flip-flops. Due to propagation delays and other inequalities in clock lines and clock flip-flops, clock skew, a slight time staggering of the clock pulses, occurs. The J-K master slave flip-flop according to the present invention is relatively insensitive to such clock skew. So long as one input to both gates is low, no change in state of the master slave flip-flop may occur. Thus, if the J-K inputs arrive at the input gates before the clock pulse arrives, no change in state occurs until the clock pulse arrives.

During the times when the clock pulse is low, the J-K inputs may change states and have no effect upon the J-K master slave flip-flop 10. The only requirement for proper operation of the flip-flop 10 is that during the time when the clock pulse is high, the J-K inputs remain constant. Since the clock pulse can be as narrow as 7 nanoseconds, this is a very low requirement of stability.

The reference diode D allows the input voltage threshold to the J-K master slave flip-flop to be set within a wide range of desired D-C levels. The threshold voltage for a high or logical 1 input is determined by the diode voltage of the reference diode D, plus the V_{be} voltages of transistors T_{01} , T_{02} , T_{12} and T_{11} . T_{11} or T_{12} will be at the voltage level $V_{diode} - V_{be}$ of T_{01} or T_{02} . For a logical 1 or high input to occur, the input voltage must be above this voltage in order the base-collector diode of T_{11} or T_{12} to be forward biased. The reference diode D allows a high D-C threshold at the input to be maintained with a minimum of circuit components and as shown in FIG. 5, provides gates G_1 — G_4 with a rectilinear transfer characteristic desirable in array applications.

It is to be understood that the above-described embodiments are merely illustrative of the invention. Other arrangements may be devised by those skilled in the art without departing from the spirit and scope of the invention.

I claim:

1. A master-slave flip-flop comprising in combination:
  - a. first and second multiple input gate circuits, each including at least one multiple emitter transistor, said first and second gate circuits being interconnected to form a master flip-flop having two output states;
  - b. third and fourth multiple input gate circuits, each including at least one multiple emitter transistor, said third and fourth gate circuits being interconnected to form a slave flip-flop having two output states;
  - c. first circuit means for interconnecting said master and said slave flip-flops; and
  - d. second and third circuit means for respectively applying plural input signals and at least one clock signal to said first and second multiple input gate circuits, said input and clock signals having at least two conditions;
  - e. said master flip-flop includes means responsive to one condition of said input signals and one condition of said clock signal for changing the state of said master flip-flop, and said slave flip-flop includes means responsive to said master flip-flop and the other condition of said clock

signal for changing the state of said slave flip-flop after said master flip-flop changes state.

2. A master-slave flip-flop in accordance with claim 1 wherein said first circuit means includes two transistors for respectively coupling the outputs of said master flip-flop to the inputs of said slave flip-flop.
3. A master-slave flip-flop in accordance with claim 1, wherein each of said second and third circuit means includes at least one multiple emitter transistor.
- 10 4. A master-slave flip-flop in accordance with claim 1 and further including fourth circuit means for applying clear and preset signals to said master and said slave flip-flops, whereby the states of said master and slave flip-flops are selectively changed in response to said clear and present signals.
- 15 5. A master-slave flip-flop in accordance with claim 1 wherein said first, second, third and fourth multiple input gate circuits are inverting gate circuits.
6. A master-slave flip-flop in accordance with claim 5 wherein said J-K signals and clock signals are selectively coupled to said master flip-flop by fifth and sixth NAND gates, with each of said NAND gates having at least one multiple emitter transistor.
- 20 7. A master slave flip-flop comprising in combination:
  - a. a master flip-flop comprising first and second interconnected NAND gates with each of said NAND gates having at least one multiple emitter transistor, said master flip-flop having two output states;
  - b. a slave flip-flop comprising third and fourth interconnected NAND gates, with each of said NAND gates having at least one multiple emitter transistor, said slave flip-flop having two output states;
  - c. circuit means for interconnecting said master and said slave flip-flops, said circuit means being responsive to J-K signals and clock signals, with each of said signals having at least a high and a low level
  - 30 d. the output state of said master flip-flop includes means responsive to one of said J-K signals and the high level of said clock signal for changing the state of said master flip-flop, and said slave flip-flop includes means responsive to said master flip-flop and the low level of said clock signal for changing the state of said slave flip-flop after said master flip-flop changes state.
  - 35 8. A master-slave flip-flop in accordance with claim 7 wherein said circuit means include first and second transistors for respectively coupling the outputs of said master flip-flop to the inputs of said slave flip-flop.
  - 40 9. A master-slave flip-flop system comprising in combination:
    - a. a master flip-flop circuit having cross-coupled multiple emitter transistors, said master flip-flop having two output states;
    - b. a slave flip-flop circuit having cross-coupled multiple emitter transistors, said slave flip-flop circuit having two output states;
    - 50 c. first and second transfer gate circuits respectively coupled between the output of said master flip-flop and the input of said slave flip-flop; and
    - d. first and second multiple input gate circuits for respectively applying plural input signals and at least one clock signal to the input of said master flip-flop, each of said input gate circuits including at least one multiple emitter transistor and said input and clock signals have at least two conditions; wherein
    - e. said input signals are selectively applied to said first and second multiple input gate circuits and said clock signal is applied to said master flip-flop; and
    - 55 f. said master flip-flop includes means responsive to one condition of said input signals and one condition of said clock signal for changing the state of said master flip-flop, and said slave flip-flop includes means responsive to said master flip-flop and the other condition of said clock signal for changing the state of said slave flip-flop after said master flip-flop changes state.
